(57) **CLAIM**

The ornamental design for a motorcycle as shown and described.

DESCRIPTION

FIG. 1 is a front and left side perspective view of a motorcycle showing our new design;

FIG. 2 is a front and right side perspective view thereof;

FIG. 3 is a front elevation view thereof;

FIG. 4 is a top plan view thereof;

FIG. 5 is a rear and left side perspective view thereof;

FIG. 6 is a rear elevation view thereof;

FIG. 7 is a left side elevation view thereof; and,

FIG. 8 is a right side elevation view thereof.

The broken lines represent portions of the motorcycle that form no part of the claimed design.

1 Claim, 8 Drawing Sheets(56)
